UNITED STATES PATENT OFFICE

118,361

DESIGN FOR A MERCHANTISE DISPLAY STOCK FIXTURE OR SIMILAR ARTICLE

Earl B. Becker, Elkader, Iowa

Application June 5, 1939, Serial No. 85,353

Term of patent 14 years

To all whom it may concern:

Be it known that I, Earl B. Becker, a citizen of the United States of America, residing at Elkader, in the county of Clayton and State of Iowa, have invented a new, original, and ornamental Design for a Merchandise Display Stock Fixture or Similar Article, of which the following is a specification, reference being had to the accompanying drawing, forming part thereof, wherein:

Figure 1 is a perspective view of a merchandise display stock fixture or similar article, showing my new design.

I claim:

The ornamental design for a merchandise display stock fixture or similar article, as shown.

EARL B. BECKER.
